CLAIM

The ornamental design for a wind threshold indicating banner, as shown and described.

DESCRIPTION

FIG. 1 is a front elevational view of a wind threshold indicating banner showing my new design;
FIG. 2 is a right side elevational view of FIG. 1;
FIG. 3 is a bottom plan view of FIG. 2;
FIG. 4 is a front elevational view of another embodiment of my new design of FIG. 1;
FIG. 5 is a right side elevational view of FIG. 4;
FIG. 6 is a top plan view of FIG. 4.
